(57) CLAIM

The ornamental design for a display screen with graphical user interface, as shown and described.

DESCRIPTION

FIG. 1 is a front view of a first embodiment of a display screen with graphical user interface, showing the display screen with a first transitional graphical user interface of the first embodiment;

FIG. 2 is another front view of the first embodiment of a display screen with graphical user interface, showing the display screen with a second transitional graphical user interface of the first embodiment;

FIG. 3 is a front view of a second embodiment of a display screen with graphical user interface, showing the display screen with a first transitional graphical user interface of the second embodiment;

FIG. 4 is another front view of the second embodiment of a display screen with graphical user interface, showing the display screen with a second transitional graphical user interface of the second embodiment;

FIG. 5 is a front view of a third embodiment of a display screen with graphical user interface, showing the display screen with a first transitional graphical user interface of the third embodiment; and,

FIG. 6 is another front view of the third embodiment of a display screen with graphical user interface, showing the display screen with a second transitional graphical user interface of the third embodiment.

The appearance of the figures sequentially transitions between FIGS. 1-2, FIGS. 3-4, and FIGS. 5-6. The process or period in which one image transitions to another forms no part of the claimed design.

The broken lines showing of text in the drawings form no part of the claimed design.

The outer edge of the portion of the display screen is understood to be congruent with the outer edge of the graphical user interface.
